(57) **CLAIM**

The ornamental design for a clip-on light, as shown and described.

DESCRIPTION

FIG. 1 is a top-left perspective view of the clip-on light of the instant invention;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top-left perspective view illustrating the instant invention secured to a pair of glasses; and,

FIG. 9 is a top-left exploded view thereof.

The portions of figures illustrated in broken lines are for environmental purposes only and form no part of the claimed design.
